UNITED STATES PATENT OFFICE.

GEORGE F. PRENDERGAST, OF BUFFALO, NEW YORK.

SPINNING-TOP.

1,089,668.

Specification of Letters Patent. Patented Mar. 10, 1914.

Application filed April 24, 1912, Serial No. 692,770. Renewed June 30, 1913. Serial No. 776,707.

To all whom it may concern:

Be it known that I, GEORGE F. PRENDERGAST, a citizen of the United States, residing at Buffalo, in the county of Erie and State 5 of New York, have invented certain new and useful Improvements in Spinning-Tops, of which the following is a specification.

My invention relates to spinning tops, and it has for its primary object the provision 10 of a top comprising two spinning members, one of which is retained on or within the other and adapted to be forcibly removed when the top is driven into contact with the ground, the spinning member forcibly removed being propelled a considerable distance in the air and caused to spin so that when it gravitates it will strike the ground with its peg and both spinning members 15 will spin at the same time.

20 A further object of my invention is the provision of a top having two spinning members, one provided with a movable peg and with a cavity and the other provided with a rigid peg and adapted to fit into the cavity of the first-mentioned member, said movable peg being driven into its member to 25 forcibly project the member having the rigid peg.

With these and other objects in view to be 30 hereinafter described, the invention consists in the novel features of construction and in the arrangement and combination of parts to be hereinafter described and particularly pointed out in the subjoined claims.

35 In the drawings,—Figure 1 is a side elevation of a top embodying my invention. Fig. 2 is a central vertical section of the top. Fig. 3 is a cross-section taken on line 3—3, Fig. 2.

40 Referring now to the drawings in detail like numerals of reference refer to like parts in the several figures.

The reference numeral 1 designates the top considered as a whole, which comprises 45 two spinning parts or members 2, 3, the spinning member 2 having a cavity 4 in its upper end, from the lower end of which extends a bore 5 which opens at the apex, as at 6. Said bore is reduced in diameter 50 at its upper end, as at 7, to provide a shoulder 8 and in its lower end is threaded or otherwise securely fastened a sleeve or ferrule 9 having a bore corresponding in diameter to that of the top at 7. Arranged slidably within the bore of the top and that of 55 the sleeve or ferrule 9 is a peg 10 having a

collar or other projection 11, said collar or projection being adapted for movement within the large portion of the bore 5 between the inner end of the sleeve or ferrule 9 and the shoulder 8, said shoulder and sleeve acting as stops to limit the movement in opposite directions of said peg. The peg has free sliding movement within the bore of member 2 and the sleeve 9 and is normally extended through the apex of the top with the collar 10 in contact with the ferrule or sleeve 9.

The spinning member 2 is preferably constructed from wood and the cavity therein is shaped to receive the spinning member 3 and retain the same in place by frictional contact. The spinning member 3 is preferably constructed of celluloid or other light material and may be hollow, as clearly 75 shown in Fig. 2, the usual methods for manufacturing hollow celluloid articles being employed for this purpose. Member 3 has a rigid peg 12 secured thereto in any suitable manner and when said member is placed 80 in position within its receiving cavity, the rigid peg 12 is in direct line with the slideable peg 10. When the spinning member 3 is placed within member 2 it projects slightly 85 above the upper edge of the latter so that the top is given an appearance resembling the standard top so generally in use. The operation of spinning the same is like that of the ordinary top, it being simply necessary to wind the string around member 2 in the usual manner and when propelling the top to the ground, the slideable peg is forced into the top by quick and powerful action caused by its impact with the ground so that the inner end thereof is brought violently 90 against the fixed peg of member 3, thus causing the latter to be projected into the air a considerable distance while spinning.

After the force imparted to member 3 to 95 propel it upwardly has been expended, said member gravitates to the ground, striking the same with its peg and spinning until the whirling force applied to it has been exhausted. This top therefore has two spinning members, both of which are caused to 100 spin upon the ground by a single unwinding of the spinning string. If desired, member 3 may be caught upon a paddle or the hand while gravitating and be retained in 105 position on the paddle or hand while spinning.

While I have shown the member 3 con-

structed of celluloid or other light material, it may, however, be constructed of wood or other material and need not necessarily be made hollow, although I have found by experience that if constructed light and made hollow it may be propelled into the air a greater distance than if made solid and of heavy material.

Member 2 may be referred to as the main top and member 3 may be termed an auxiliary top, and while the construction shown and described is now considered the preferred, minor changes in construction may be resorted to without departing from the spirit of my invention or sacrificing any of the advantages thereof.

Having thus described my invention, what I claim is,—

1. In combination in a top, two top members, one carrying the other and having a movable element adapted to project said other upwardly when the top is brought in contact with the ground.

2. A spinning top comprising a main top having a movable peg and an auxiliary top carried by said main top and adapted to be driven into the air by the movable peg of said main top.

3. A spinning top comprising a main top having a cavity in its upper end and a slideable peg normally projected and adapted to

be moved into the main top when brought in contact with the ground, an auxiliary top held within the cavity of said main top and having its peg in line with the slideable peg 35 of said main top and adapted to be forcibly engaged by said slideable peg to cause the auxiliary top to be driven from its cavity while spinning said main top.

4. A spinning top comprising a main top 40 having a cavity in its upper end and a shouldered bore extending downwardly from said cavity, a ferrule fitting into said bore from the apex of the top, a peg slideable in said ferrule and bore and having a collar adapted to engage the shoulder of said bore and the inner end of said ferrule in its opposite movements, and an auxiliary top held in said cavity by frictional contact and having a fixed peg adapted to be engaged by the inner end of said slideable peg when the top is 50 propelled to the ground so as to project the auxiliary top from its cavity while both pegs are spinning.

In testimony whereof, I have affixed my 55 signature in the presence of two subscribing witnesses.

GEORGE F. PRENDERGAST.
